UNITED STATES PATENT OFFICE.

MAX WIESE, OF BOSTON, MASSACHUSETTS.

DESIGN FOR A TILE FLOOR OR PAVEMENT.

SPECIFICATION forming part of Design No. 15,780, dated February 3, 1885.

Application filed August 12, 1884. Term of patent 14 years.

To all whom it may concern:

Be it known that I, MAX WIESE, of Boston, in the county of Suffolk and State of Massachusetts, have invented and produced a new 5 and original Design for a Tile Floor or Pavement, of which the following is a full, clear, and exact description.

My design for a tile floor or pavement consists in a peculiar configuration of the tiles 10 and in the assembling of said peculiar-shaped tiles to produce an ornamental pattern of different colors, substantially as hereinafter specified.

Reference is had to the accompanying drawing, forming a part of this specification, and which represents an upper face view of a piece 15 of flooring or paving tiling embodying my design.

A A' indicate the tiles of different colors, 20 but each of which is of similar configuration, and has a marginal profile that consists of two reverse concave sides, *a a*, and two reverse convex ends, *b b*, the radii of said sides and ends being equal, and the centers from which 25 they are struck being in or on straight lines intersecting each other at right angles in the center of the tiles, as shown by dotted lines. The tiles A A' thus present ornamental figures 30 of equal concave and convex curvature on their sides and ends, and so that when assem-

bled their convex margins match with the concave margins of the next adjacent tiles, thus presenting an ornamental checkered pattern made up of curved figures, in which either one set of tiles A A' are intercepted at their convex ends by the concave sides of the other or crossing set of said tiles, and the ornamental effect thus produced is greatly augmented by having the several tiles of different colors, or the one set of tiles, A, of one 40 color, as represented by cross lines, and the other set of tiles, A', of another color.

I claim—

1. The within-described design for a floor or pavement tile, which consists in a marginal profile or configuration made up of two 45 reverse concave sides and two reverse convex ends, all having the same length of radii, as shown.

2. The within-described design for a tile 50 floor or pavement, which consists of tiles of different colors, but each of a like marginal configuration, composed of two reverse concave sides and two reverse convex ends, all having the same length of radii, and the whole 55 being assembled as shown and specified.

MAX WIESE.
